IMPROVED CAR BRAKE.

LOUIS ALEXIS VELU, EUGENE FRANCOIS FOSSE, AND LOUIS EUGENE ALPHONSE FOSSE, OF PARIS, FRANCE.

Letters Patent No. 60,094, dated November 27, 1866.

SPECIFICATION.

TO ALL WHOM IT MAY CONCERN:

Be it known that we, LOUIS ALEXIS VELU, EUGENE FRANCOIS FOSSE, and LOUIS EUGENE ALPHONSE FOSSE, all of Paris, in the empire of France, have invented a new and improved Arrangement for Stopping or Retarding Railway Carriages, Cars, Trucks, or other rail or tram-road vehicles; and we do hereby declare that the following is a full and exact description thereof, reference being had to the accompanying drawings, and to the letters of reference marked thereon.

The invention relates to an improved mechanical arrangement for stopping or retarding railway carriages, wagons, cars, trucks, locomotives, tenders, vans, or other vehicles, either for rail or for tram roads, whether driven by steam or other mechanical power, or by horse or other animal power, which arrangement is to be applied to one or several of the carriages of a train, and by means of which arrangement one or more pairs of wheels of the cars or carriages may, whilst in motion, be lifted at the height required for carrying the said wheels out of contact with the rails, the arrangement consisting mainly of a wedge-shaped block, which at the required moment is to be inserted between the rail and a suitable prop or stay fixed against the lower part of the frame or the buffer bars of the car or other vehicle.

In order to make the invention more readily and completely understood, we will now give a full description of the same, referring thereby to the annexed drawings, in the various figures of which the same letters relate to corresponding parts.

Figure 1 shows a longitudinal side or elevation view of a luggage van or wagon provided with our improved stopping or retarding apparatus.

Figure 2 shows a back view; and

Figure 3 a view from underneath of the same.

In the figs. 2 and 3 only those parts are represented as relate more particularly to our stopping arrangement, and in the fig. 1 the arrow, 1, shows the direction in which the carriage is to move.

Before entering into the details of the invention, we wish it to be understood that we do not intend to limit ourselves to any particular means or mechanical contrivance for actuating our stopping or retarding apparatus, viz, for inserting at the required moment the stopping wedges or blocks between the rails and the respective fixed stays or props, of withdrawing the said wedges or blocks, neither to any particular means of connecting together and causing to work in connection the stopping wedges or blocks of several carriages of a railway train, as various mechanical arrangements may be resorted to for these purposes, though we will describe here an arrangement which we intend to make use of for the said purposes.

As has been mentioned above, our stopping or retarding apparatus is based on a principle differing entirely and contrary to what has been done hitherto in apparatuses of this kind, for instead of acting on the wheels of the carriages for the purpose of causing an increase of friction to be created between the said wheels and the rails, by transforming the rotary or rolling motion of the wheels into a sliding or skidding one on the rails, the principle of working of our improved arrangement consists in lifting at the required moment the carriage or cause the same to rise to such height above the rails as fully to prevent any further contact to take place between the wheels of the carriage and the rails, the stopping or the retarding of the motion of the carriage being procured by the friction exerted on the rail by a wedge-shaped block interposed between the rail and a prop or stay solidly fixed against the lower surface of the frame of the carriage or the buffer bars of the same, and so as to cause the weight of the carriage to press on the said wedge-shaped blocks along the inclined surface of which the impetus of the carriage causes the same to ascend, by means of the just-mentioned props or stays, thereby causing also a considerable amount of friction to be created between the inclined surface of the blocks and that of the props or stays, one of which latter is situated in front of each of the wheels of the carriage, and securely fixed to the frame of this latter, whilst for each of the said props or fixed stays a wedge-shaped stopping block is provided, the latter to act in combination therewith. The various stopping blocks of each carriage are connected together so as to cause all of them to act simultaneously, whilst those of several successive carriages of a train may likewise be connected together by suitable rods, chains, wires, or other similar means.

A¹ A² A³ A⁴ represent the wheels of a four-wheeled luggage van, wagon, or other similar railway carriage.

B¹ B² show the rails, C the frame of the carriage, suspended in the usual manner on the axles by means of the springs, D. E¹ E² E³ E⁴ are four wrought or cast-iron props or resting stays bolted or otherwise securely fixed to the lower part of the frame or to the buffer bars of the carriage; the side of the prop turned toward the wheel, in front of which the same is situated, should preferably offer a curve corresponding about with that of the wheel, but of course leaving the necessary distance apart for the working of this latter. The lower surface of

the prop, namely, that situated immediately above the rail, presents an incline which is about to correspond with that of the upper or inclined surface, g , of the wedge-shaped stopping block, G , which, when the carriage is to be stopped, is inserted for a suitable length between the prop and the rail. The hind part of each of the stopping blocks, G , which blocks are to be made of cast or wrought iron, or steel, presents on the upper side an incline, g , the angle of declivity of which corresponds about with that of the inclined lower surface of each of the props, E . This incline, g , might be made to turn on a hinge situated at the end, p , of the wedge, whereas the other end of this incline g might be kept at the required height by a lever, or other suitable means, so as to allow of setting the same at the required degree of declivity. It will be understood that in such case the blocks, G , instead of forming one solid piece of cast or wrought iron, or steel, is to have its inclined part, g , formed of a strong slab or plate of wrought iron hinged in p , to the nib or hind end of the block. The fore part, g' , of the block is provided with two small uprights or standards, h , between which is inserted a horizontal cross-bar, H , in such manner that by causing this bar to recede, namely, in the direction of the arrow, 2 , part of the incline, g , of the block will become inserted between the rail and the fixed prop, whereas by pushing the bar, H , in the direction of the arrow, 1 , the incline g of the block G will be withdrawn from under the fixed prop, particularly if done in combination with the lowering of the incline g . A flat bar, I , is inserted in corresponding holes provided in the uprights h ; the ends of this bar, I , are fixed in the prop E , the shape of which latter may be seen in fig. 1. The bar I is set in an inclined position corresponding with that of the holes in the uprights, h , in such manner that in gliding by means of these uprights along the bar I , the block G , in receding toward its corresponding wheel, will be lowered and thereby part of the incline g become inserted between the wheel and the rail. At each end the bar H is bent upward at right angles, and at i the same is bolted to the links K^1 and K^2 , which latter connect together the rods L^1 and L^2 at one side and those L^3 and L^4 at the opposite side of the carriage. The rods L^1 and L^3 , again, are jointed to the short arms M^1 and M^2 of the levers $M^1 M^3$ and $M^2 M^4$, which latter turn in opposite directions on a central bolt N in a bracket N' fixed to the lower side of the frame of the carriage. By means of these levers, $M^1 M^3$ and $M^2 M^4$, the required advancing and receding motions may be imparted to the blocks, G , so as either to cause incline g to enter more or less into the open space left between the rail and the lower surface of the corresponding fixed prop or stay, or to become withdrawn therefrom. Various mechanical arrangements may be resorted to for imparting the necessary motion to the levers $M^1 M^3$ and $M^2 M^4$. We will describe here one of the arrangements which may be applied for that purpose: To the ends, M^3 and M^4 , of the levers, $M^1 M^3$ and $M^2 M^4$, are jointed two racks, P^1 and P^2 , both in gear, but in opposite directions, with a pinion Q , the vertical spindle R of which turns in brackets, S , fixed to the end of the carriage, the spindle being provided with a handle, T , for allowing to turn the pinion in the required direction, either for causing the racks P^1 and P^2 to recede or to advance on the pinion Q , and thereby work the levers $M^1 M^3$ and $M^2 M^4$, and consequently the blocks, G , connected to them. It will be readily understood that by means of suitable connecting rods, chains, wires, or other similar means, the rods L^1 and L^2 and links K^1 and K^2 of several successive carriages of a train may be connected, and thus the various stopping blocks be worked simultaneously and be put either under the command of the guard, the engine driver, or other attendant; if wished, the bolts, N , of the various carriages might be connected in a similar manner, and by means of them motion be transmitted to the various stopping blocks. We do not, however, intend to limit ourselves to any particular mode of connecting together and causing to work simultaneously the various stopping blocks of one or of several carriages of a train.

The mode of working of our apparatus is as follows: Supposing fig. 1 to represent a luggage van or wagon forming the end of a railway train consisting of several carriages, each of them provided with our improved stopping apparatus, namely, with the fixed props or stays, E , the stopping blocks G and parts required for working or actuating these latter, the handle, T , to be within reach of the guard of the train or other attendant. In case of a sudden danger, requiring the speed of the train to be retarded or stopped as quick as possible, the guard or other attendant will simply have to turn the handle, T , and cause the pinion, Q , to turn in the direction required for causing the free ends of the long arms, M^3 and M^4 , of the levers $M^1 M^3$ and $M^2 M^4$ of becoming expanded by the effect of the racks P^1 and P^2 , which will cause the short arms, M^1 and M^2 , of the said levers to carry the cross-bar H toward the corresponding wheels of the carriage, and consequently drive the blocks, G , between the rails and the respective fixed props, E , while by the impetus of the carriage these fixed props will glide with their inclined lower surface along the incline g of their respective stopping blocks, G , and thereby cause the carriage to be lifted sufficiently high above the rails for carrying the wheels out of contact with these latter, and thus cause the entire weight of the carriage to press upon the block G ; the friction thus created between these latter and the rails and between the under side of the props, E , and the incline, g , of the blocks, will be sufficiently intense for obtaining a very rapid retarding of the motion of the carriages, and consequently the stopping of the train.

Having thus described the nature of our invention, and the manner in which the same is or may be put into operation, what we consider to be novel and original, and therefore claim as our invention, is—

Combining with a lever, or its equivalent, for operating the brake, and with the frame or wheels of a car or other similar carriage, the brake-blocks E and wedges G , constructed and arranged to operate in the manner and for the purpose substantially as described.
